DESIGN FOR A COMPACT

James Murray Beveridge, Bronxville, N. Y.

Application June 1, 1945, Serial No. 119,835

Term of patent 7 years

(Cl. D86—10)

To all whom it may concern:

Be it known that I, James Murray Beveridge, a citizen of the United States of America and a resident of Bronxville, in the county of Westchester and State of New York, have invented a new, original, and ornamental Design for a Compact, of which the following is a specification, reference being had to the accompanying drawing, forming a part thereof.

In the drawing:

I claim:

The ornamental design for a compact, as shown.

JAMES MURRAY BEVERIDGE.
